SPACE STATION

Saunders B. Kramer, Sunnyvale, and Engbertus H. Vischer, San Jose, Calif., assignors to Lockheed Aircraft Corporation, Burbank, Calif.

Filed Aug. 4, 1960, Ser. No. 61,630

Term of patent 14 years

(Cl. D71—1)

FIG. 2

FIGURE 1 is a perspective view of a space station showing our new design;

FIGURE 2 is a side-elevational view thereof, and

FIGURE 3 is an enlarged cross-sectional view on the line 3—3 of FIGURE 2 illustrating the rear of the radiator member.

Our design for the space station disclosed, comprised of a plurality of cylindrical modules and interconnecting spherical members, is characterized by the axial extensions thereof; one of the axial extensions including a series of cooling fins, a nuclear reactor housing, a radiation shield, and a radiator member, and the other of said axial extensions includes a series of flat disc-shaped landing pads.

We claim:

The ornamental design for a space station, as shown and described.
